UNITED STATES PATENT OFFICE

CHESTER N. MOORE, OF SCHENECTADY, NEW YORK, ASSIGNOR TO GENERAL ELECTRIC COMPANY, A CORPORATION OF NEW YORK.

TERMINAL FOR METAL-SHEATHED WIRE.

1,077,734.

Specification of Letters Patent.

Patented Nov. 4, 1913.

Application filed January 18, 1913. Serial No. 742,830.

To all whom it may concern:

Be it known that I, CHESTER N. MOORE, a citizen of the United States, residing at Schenectady, county of Schenectady, State of New York, have invented certain new and useful Improvements in Terminals for Metal-Sheathed Wire, of which the following is a specification.

My invention relates to wire which comprises an electrical conductor covered with insulation and with a metal sheath.

More particularly my invention relates to the terminal connections for such wire.

The purpose of the metal sheath is to protect the insulation against wear and to hold it in close contact with the inner conductor. It is essential that the inner conductor be effectively insulated from the sheath because otherwise short circuits and leakage of current would be occasioned. The problem of providing a suitable terminal for this wire is one of considerable difficulty. Especially is this true in cases where the inner conductor is small in cross section as when the wire is used in heating and other electrical resistance apparatus. In the first place, the terminal connection must be made without electrically connecting the inner conductor and the sheath. Then the union must be sufficiently rigid and strong so that it will resist bending stresses. Furthermore, the union should be such that it will not be burned away due to the high temperature to which the inner conductor is raised when the apparatus is in use.

The object of my invention is to produce a terminal connection which will possess all these requisites and, which at the same time, will be simple in construction.

According to my invention I interrupt the electrical conductivity of the sheath at a point intermediate of its ends. I prefer to accomplish this by means of a small continuous gap in the sheath located a short distance from the end to be provided with the terminal connection. I then unite the inner working conductor to the sheath at the end by means of a body of metal. In this way a terminal is produced which possesses the mechanical strength of the entire section of the wire and at the same time, does not impair the insulation of the main or body portion of the sheath from the inner conductor. Preferably I surround the gap in the sheath by a bushing or sleeve of

insulating material which is sufficiently rigid to prevent the wires from being bent at this point and immediately adjacent thereto. This prevents the displacement of the insulation from around the inner conductor and also prevents breaking of the inner conductor adjacent to the point of union of the external circuit. In the preferred form of my invention I unite a terminal pin to the inner conductor and to the sheath, but this is not essential thereto.

My invention will be more clearly understood by reference to the accompanying drawing, in which—

Figure 1 is a vertical section of the parts of a terminal embodying my invention before the assembly thereof; Fig. 2 is a vertical section of the completed terminal; and Fig. 3 is a vertical section of a modification.

As shown in Figs. 1 and 2, a portion of the sheath 10 is removed, as by filing, to form a continuous gap 11 and to expose the insulation 12 which may be lime or other material commonly used in connection with sheath wire and which is firmly compacted around the inner conductor 13. A sleeve 14 which may be of hard rubber, fiber, lava, or other durable and rigid insulating material is then slipped over the end of the sheathed wire into such a position that it bridges the gap 11 and it is then fastened in place as by cementing at 15. The terminal pin 16 is then united at 17 to the ends of the sheath 10 and the inner conductor 13 as by brazing or other well known processes. In Fig. 2 the completed terminal is shown.

In Fig. 3 is shown a modification of the above described structure in which instead of providing a terminal pin 16 the inner conductor 13 is connected to the end of the sheath 10 by a body of solder or other brazing material 18. In all other respects this terminal is the same as that above described.

In both of the forms of my invention above described the inner conductor and the sheath are connected at the ends thereof and the cross sectional area of the terminal is therefore considerably greater than that of the inner conductor. This gives to the first described form a more rigid support for the terminal pin 16 than would be the case if the same were united only to the inner conductor. In the other form a terminal pin is formed through which a much stronger connection may be made to an external cir-

cuit than if the said connection were made merely to the end of the inner conductor. In both forms the interruption in the sheath prevents the main portion of the same from being included in the electric circuit and the insulating sleeve prevents bending or other displacement of the parts of the terminal.

Various modifications of the above described structure will suggest themselves to those skilled in the art and are to be considered as coming within the scope of the same as set forth in the annexed claims.

What I claim as new and desire to secure by Letters Patent of the United States, is:

1. The combination of a wire comprising an inner working conductor, an outer metallic sheath, and insulation between said conductor and said sheath, said sheath having its electrical conductivity interrupted intermediate its ends, and means for electrically uniting an end of said conductor to the corresponding end of said sheath.
2. The combination of a wire comprising an inner working conductor, an outer metallic sheath and insulation between said conductor and said sheath, said sheath having its electrical conductivity interrupted intermediate its ends, and a terminal pin united to the said sheath and to the said conductor at an end of said wire.
3. The combination of a wire comprising

an inner working conductor, an outer metallic sheath and insulation between said conductor and said sheath, said sheath having a small continuous gap therein intermediate its ends, an insulating sleeve surrounding said gap, and means for electrically uniting said conductor to said sheath at an end of said wire.

4. The combination of a wire comprising an inner working conductor, an outer metallic sheath and insulation between said conductor and said sheath, said sheath having a small continuous gap therein adjacent to an end thereof, an insulating sleeve surrounding the said gap, and means for electrically uniting said conductor and said sheath at the said end.

5. The combination of a wire comprising an inner working conductor, an outer metallic sheath and insulation between said conductor and said sheath, said sheath having a small continuous gap therein adjacent to an end thereof, an insulating sleeve surrounding the said gap, and a terminal pin united to said sheath and to said conductor at the said end.

In witness whereof, I have hereunto set my hand this 17th day of January, 1913.

CHESTER N. MOORE.
